MOP

James H. Follen, Spring Lake, Mich., assignor to
Gem Hammock & Fly Net Company, Milwaukee,
Wis., a corporation of Wisconsin

Application March 7, 1938, Serial No. 194,306

6 Claims. (Cl. 15—152)

This invention relates in general to the attachment of a metal head at the end of a handle or stick and has more particular reference to a mop.

An important object of the invention is in the provision of improved means for attaching an implement head at the end of a handle or stick.

A further object of the invention is in the provision of improved means for interlocking and securing a metal head to a handle.

A still further object of the invention is in the provision of a mop head made from a single blank of material cut and formed to provide a mop head with overlapped handle embracing projections having handle piercing tangs.

In the accompanying drawing illustrating preferred embodiments of the invention,

Fig. 1 is a side elevation of a mop constructed in accordance with the principles of this invention;

Fig. 2 shows a blank from which one of the heads is made;

Fig. 3 is an end elevation of the head as shown in Fig. 1;

Fig. 4 is a section taken on the line 4—4 of Fig. 3;

Fig. 5 is an end elevation of a head showing a modified form of clinching attachment; and

Fig. 6 is a section taken on the line 6—6 of Fig. 5.

Although this invention is particularly described in my U. S. Patent No. 2,164,395, of July 4, 1939, for Mop holder, of which it is a continuation in part, as applied to a head for a mop, a similar interlocking attachment may be used for connecting the heads of other utensils at the end of a stick, such as rakes, hoes, and any other implement in which it is desired to securely attach a metal part to a wooden stick or handle.

The mere clinching of the edges of opposite side members into a supporting stick or handle is not usually sufficient to hold a metal head securely connected to a stick. This is particularly true where the implement is subjected to severe pushing, pulling and torsional strain, and is more particularly true in the case of a mop or other implement which is alternately wet and dry, for the wood either shrinks or loosens, or the clinched portions of the head work loose and allow a relative angular movement between the head and the stick which soon destroys or loosens the connection.

The present invention overcomes these objections by providing a plurality of points of attachment for the mop head spaced along and at

different points around the stick, with the attached portions overlapped or staggered at opposite sides and also clinched into the handle itself at spaced distances and in different directions so that a portion of the handle between the inserted tangs is in fact interlocked so that there is less tendency for the head to loosen even under great strain and it will be held tightly in place.

Referring now more particularly to the drawings, a mop head 7 is attached at the end of a handle or mop stick 8 and a mop cloth 9 is clinching held in a bottom groove 10 of the head by a clamping wire 11, the extremities 12 of which are bent and engaged in opposite sides of attaching lever 13. Interposed between the clamping lever 13 and the head and surrounding the stick is an extending coil spring 14, one end held in connection with the lever by an eyelet 15 through which it extends and the other end of the spring held in connection with the head by a tongue 16 pressed out of the metal of the head and clinched over the head of the spring wire at this end.

The location of the lever and its attachment to the spring is such that when pressed downwardly against the handle 8 about the eyelet 15 as an axis it draws the clamping wire 11 tightly within the groove 10, binding the mop cloth 9 yielding therein and holds the lever 13 yielding against the stick from which it can be disengaged only by manually raising the outer or handle end of the lever from the stick.

The head is made up of a blank of sheet metal cut as shown in Fig. 2, and shaped by suitable dies as shown in Fig. 1. At opposite ends of the blank are notches 18 which define the clamping wire groove and at opposite sides of the blank are side projections 19 connected with the main portion of the blank by reduced neck portions and each having opposite reduced projections 20 and 21 adapted to be bent at the extremities to form tangs inserted under pressure into the mop stick, these projections lying one above the other as shown more clearly in Fig. 3 so that they are staggered or overlap. The extremities 22 which are inserted may be sharpened or pointed at the ends but preferably are inserted axially and since the projections 20 and 21 of opposite sides overlap the extremities 22 as shown in Fig. 4, substantially engage a wedging projection between them on each side of the stick which tend to hold the head clamped more firmly at the end of the stick.

Instead of overlapping to the extent shown in Figs. 3 and 4 the projections of the sides may overlap only slightly as shown in Figs. 5 and 6,

in which case the inserted tangs or extremities 24 are substantially in alignment. Even in this form the extremities are preferably clinched inwardly and oppositely as indicated in Fig. 6, so that they 5 will grip the stick more firmly and will have a wedging or divergent attachment therewith. In both cases the overlapping projections of the sides 19 serve to accurately position the side projections and locate the insertion of the inwardly bent 10 tangs at the extremities of the projections. The parts of the opposite side projections which overlap also substantially interlock at the sides when the tangs are inserted and thus strengthen the attachment of the head to a stick. When the 15 tangs are out of alignment at each side of the stick the tendency is to prevent the stick from splitting and when the extremities are inclined oppositely as shown in Fig. 6, they tend to grip the opposite sides of the stick more firmly be- 20 tween each of the opposite sides of the blank.

I claim:

1. A mop head fastening in combination with a handle, comprising a single sheet of metal bent in the center and having complementary 25 handle socket portions formed at opposite sides, each side portion having projections extending oppositely at different distances from the center of the blank and overlapping the opposite side projections at different distances from the center 30 when they are bent to form a socket, and the extremities of both projections at each end being turned inwardly, piercing the handle, the handle piercing projections being out of alignment at each side of the handle.
- 35 2. In a mop stick fastening, a cross head of sheet material having opposite complementary sections forming a socket to secure the head to the stick, each of the socket forming sections having opposite projections at different distances 40 from the crosshead with handle piercing tangs at both extremities, the projections of the opposite sides being staggered so that they will overlap at opposite sides of the stick, and the tangs being acutely bent to enter the stick for securing 45 the head firmly to the stick by the overlapping engagement of said projections.
3. A mop stick fastening comprising a stick and a head therefor, comprising a single sheet of metal bent to form opposite complementary sec- 50

tions for forming a socket to secure the head to the stick, the socket sections both having opposite projections at different distances from the head with inwardly turned tangs at the ends inserted into the stick, the tang of one section 5 overlapping that of the other along the stick and providing an interengagement with the stick sections between the tangs at opposite sides for interlocking the said opposite complementary sections in positioning and firmly attaching them 10 to a stick.

4. A mop head fastening comprising a stick and a cross head of sheet material therefor, the sheet material being bent to provide complementary sections forming a socket to secure the head 15 to the stick, each section having opposite projections at different distances from the head along the stick with tangs at the ends, the outer tang at the end of one section overlying the inner tang at the end of the other section along the stick, 20 and the adjacent tangs at each side of the stick being inserted therein at different angles to bind the stick more securely.

5. A mop head fastening comprising a handle 25 stick and a cross head of sheet material having opposite complementary sections rounded together forming a socket to secure the head upon the stick, each section having opposite projections at different distances from the head with inwardly turned tangs at the ends to engage the handle, the outer projection of one section overlying the inner projection of the other section 30 along a handle, the corresponding projections of opposite sections abutting each other and both completely surrounding the handle when the 35 tangs are inserted in the handle.

6. A mop handle fastening means comprising a sheet metal head bent at the center and opposite complementary socket portions each bent semi-circularly and having opposite projecting 40 portions at different distances from the center and one overlapping the other along the stick with bent tang portions at the opposite ends, the portions in alignment along the stick both embracing the stick and abutting the tangs 45 which extend into the handle, the adjacent tangs at the same side being at different angles to grip the handle therebetween.

JAMES H. FOLLEN.
